DESIGN FOR A SLIPPER

John D. Ferriso, Brooklyn, N. Y.

Application May 29, 1945, Serial No. 119,798

Term of patent 7 years

(Cl. D7—7)

To all whom it may concern:

Be it known that I, John D. Ferriso, a citizen of the United States of America, residing in Brooklyn, county of Kings, and State of New York, have invented a new, original, and ornamental Design for a Slipper, of which the following is a specification, reference being had to the accompanying drawing, forming part thereof.

Fig. 1 is a front perspective view of a slipper showing my new design.

Fig. 2 is a bottom perspective view thereof.

I claim:

The ornamental design for a slipper, substantially as shown.

JOHN D. FERRISO.
